G. P. HEMSTREET

CONTAINER

Filed May 9, 1919

Fig. 1.

Fig. 2.

Inventor:
George P. Hemstreet,
Orchard, Ruth, Janey & Nancy
Addys.

UNITED STATES PATENT OFFICE.

GEORGE P. HEMSTREET, OF HASTINGS-UPON-HUDSON, NEW YORK.

CONTAINER.

Application filed May 9, 1919. Serial No. 295,972.

To all whom it may concern:

Be it known that I, GEORGE P. HEMSTREET, a citizen of the United States, and a resident of Hastings-upon-Hudson, Westchester County, N. Y., have invented an Improvement in Containers, of which the following description, in connection with the accompanying drawings, is a specification, like characters on the drawings representing like

10 parts.

This invention relates to containers, more especially bottles used for pills, tablets and the like, and aims to provide convenient and easily-operated means to compact the mass 15 of material, and to prevent breakage and abrasion of the tablets, which is apt to occur if the mass is left loose and free to rattle about within the bottle. The invention also aims to obviate the inconvenience at 20 tending the use of a tuft of cotton usually employed between the stopper and the mass of material to reduce the air space, and to prevent injury to the contents.

My invention will be best understood by 25 reference to the following description, when taken in connection with the accompanying drawings of one illustrative embodiment thereof, while its scope will be more particularly pointed out in the appended claims.

30 In the drawings:

Fig. 1 is a perspective view of a container equipped with a device exemplifying my invention; and

Fig. 2 is a vertical sectional view of the 35 same, showing the container filled with tablets.

Referring to the drawings, and to the specific embodiment of my invention which is selected for exemplification, I have shown 40 a container comprising a bottle 3, provided with a neck 4, having an opening 5 normally closed by a suitable closure, herein a usual stopper 6, which is fitted into the neck in the customary manner.

45 In Fig. 2, I have shown the bottle containing a mass of tablets or lozenges 7, which are usually more or less fragile and likely to be injured by rattling about within the bottle. As a means to compact the mass of material, I have provided a follower, herein comprising a body of suitable yielding material, preferably a disc or other suitably-shaped layer of cotton 8, preferably stiffened 50 by a reinforcing member, which may conveniently consist of a disc 9 of appropriate

material such as pasteboard disposed beneath the layer of cotton.

Suitable means are provided to move the follower toward and from the opening 5 in the neck of the bottle, and for this purpose, 60 I have herein provided a flexible member, preferably comprising a cord 10 having one end secured to the follower, as by being passed therethrough, and provided with a knot 11 therebeneath, said cord extending 65 from the follower in an upward direction to the exterior of the bottle, preferably by providing the stopper 6 with an axial hole 12, through which the cord extends. If desired, the outer end of the cord may be provided with an enlargement, such as a knot or ball 13 attached thereto. That part of the cord which is outside the bottle may be suitably secured in the desired position of adjustment, as by wrapping the same about 70 the stopper 6, as clearly shown in the drawings.

When the container is in use and it is desired to remove some of its contents, the stopper is first removed, it being understood 80 that the latter will slide along the cord toward the outer end of the latter. The cord is then pulled in an upward direction, thus raising the contents to the under side of the neck, whereupon the desired amount 85 can be shaken out of the bottle. The stopper is then restored to its proper position, and the cord is again pulled in an upward direction, to cause the mass to be compacted. Finally, the end of the cord is wrapped 90 about the cork and suitably fastened, as by tying the same. Thus the contents of the bottle are always kept in a minimum air space, and cannot be broken or abraded, no matter how much of the contents may be removed.

Having thus described one embodiment of my invention, but without limiting myself thereto, what I claim and desire by Letters Patent to secure is:

1. The combination with a container and a closure therefor provided with an opening, of a follower, and follower operating means extending through said opening and operable from the exterior of said container 105 to compact solid matter between said follower and said closure when said closure is applied thereto.

2. The combination with a container and a closure therefor, of a follower, and fol- 110

lower operating means having one end attached to said follower and the other end disposed externally of said container and attached to said closure to maintain said follower at the desired height.

3. The combination with a container and a closure therefor, of a follower substantially filling the area encompassed by the lateral wall of said container, and follower operating means extending through said closure.

4. The combination with a container and a closure therefor, of a follower, and follower operating means attached to said closure and maintaining said follower at the desired height.

5. The combination with a container and a closure therefor, of a follower and follower operating means extending through said closure and adjustably attached thereto, thereby at will to maintain said follower at various desired heights.

6. The combination with a container and a closure therefor provided with an opening, of a follower, and follower operating means comprising a flexible member attached to said follower and extending through said opening to the exterior of said container.

7. The combination with a container and a closure therefor, of a follower, and follower operating means comprising a flexible member attached to said follower, extending through said closure and wrapped about a portion of the latter.

8. The combination with a container and a closure therefor, of a follower comprising a body of compressible material, and means for moving said follower toward and from said closure.

9. The combination with a container and a closure therefor, of a follower comprising a body of yielding material, reinforcing means for said follower, and means for moving said follower toward and from said closure.

10. The combination with a container and a closure therefor, of a follower comprising a body of soft, fibrous material, and means for moving said follower toward and from said closure.

11. The combination with a container and a closure therefor of yielding means carried by said closure for compacting the material within said container.

In testimony whereof, I have signed my name to this specification.

GEORGE P. HEMSTREET.
